Lacy, Lacy, Attorneys.

Inventor
Maude Luder.

UNITED STATES PATENT OFFICE.

MAUDE LUDEK, OF ASBURY PARK, NEW JERSEY.

ANKLE BRACE.

Application filed September 21, 1925. Serial No. 57,738.

This invention relates to an improved form of ankle brace and has as its general object to provide an ankle brace which will afford relief to those who suffer with swollen 5 and painful ankles as result of continuous standing, walking, dancing, or any other pedal exertion.

More specifically, the invention has as its object to provide a brace designed especially 10 to be worn while resting or sleeping and which will relieve the swelling and pain incident to over-exertion of the muscles of the foot and ankle, so as to restore the muscles to their normal condition.

Another object of the invention is to provide an ankle brace which may be worn with 15 extreme comfort and no inconvenience and which will reduce the swelling in the ankle joint and relieve the strain which has been 20 imposed thereon.

Another object of the invention is to so construct the brace that when applied, it will not be liable to become displaced but will maintain such a position upon the ankle 25 as to support and hold the same in its natural position and, therefore, influence the muscles to assume such position and maintain the same while standing, walking, dancing, or otherwise exercising the feet and 30 limbs.

Another object of the invention is to provide an ankle brace which may be readily and conveniently adjusted to snugly embrace the ankle without causing discomfort to the 35 wearer and in a manner to properly conform to the actual shape of the ankle,

Another object of the invention is to so construct the brace that, while made of flexible material, it will not be subject to 40 puckering while and after being adjusted or fitted to the ankle.

In the accompanying drawings:

Figure 1 is a perspective view illustrating the ankle brace embodying the invention applied.

Figure 2 is a view illustrating the ankle brace spread out.

Figure 3 is a horizontal sectional view through the brace, taken substantially on 50 the line 3—3 of Figure 1.

Figure 4 is a similar view taken substantially on the line 4—4 of Figure 1.

The brace embodying the invention may be made from any suitable flexible material 55 such as leather or a washable fabric and the same comprises a body portion indicated in

general by the numeral 1, which is adapted to embrace the ankle, the body of the brace including a back portion 2 and side portions 3 and 4. The said body of the brace preferably has a substantially straight upper margin 5 which may be suitably bound, as illustrated in the drawings, and the back portion 2 is vertically divided throughout a portion of its height at its upper part 60 and a gusset 6 is inserted at this point and stitched as at 7, to the opposite sides of the incision, thereby providing a desirable fullness to adapt the brace to fit about the leg immediately above the ankle, and this 65 gusset may be of the same material as the body of the brace or, if found expedient, it might be made of some other material and might even be elastic. A substantially circular opening 8 is provided in the lower 70 portion of the body of the brace to accommodate the heel, as clearly shown in Figure 1 of the drawings, and a binding 9 is preferably provided about the margin of the material defining this opening. The lower 75 margin of the body, indicated by the numeral 10, is extended on a curved line, and by reference to Figure 1 of the drawings, it will be observed that the portion of the brace between the opening 8 and the margin 80 10 is narrower at its said portion so as to comfortably engage against the under side of the heel, and that this portion is of gradually increasing width where it merges 85 with the side portions of the brace. It will 90 likewise be observed by reference to Figure 1, that the gradually widening sides of the heel or instep embracing portion, which is indicated by the numeral 11, snugly fit 95 against the opposite sides of the heel and conform to the shape thereof.

It is preferable that the body of the brace be made from two pieces of material united along a straight line, by stitching, as indicated by the numeral 12, at one side of the 100 heel or instep embracing portion 11, and along a curved line, as indicated by the numeral 13, likewise by a stitched seam which extends from the opening 8 at one side thereof to the upper margin 5 of the body of the 105 brace at the corresponding side. The provision of this seam 13 and the seam 12 adapts the body to be made of a shape to conform snugly to the contour of the ankle and lower portion of the leg, as will be 110 observed by reference to Figure 1, and it will be evident at this point, that should it

be desired to do so, the seam 13 may be opened and more or less of the material at either or both sides thereof cut away and the material again stitched to restore the seam, in adapting the brace to fit ankles of different contours and sizes, it being desirable that the brace snugly embrace the ankle and conform closely to the contour thereof. Furthermore, by providing the seam 13 and the seam 12, which seams diverge toward the front of the brace, the lower portion of the body of the brace may be made to assume a concave form and be thus adapted to conform to the heel of the foot as well as to the ankle. It will be observed by reference to Figure 1, that when the brace is applied, the heel of the foot will seat in the opening 8 and the instep embracing portion 11 will fit snugly beneath the instep and the forward portion of the heel and against the sides of the instep and the heel. It will also be evident that the seam 13 will extend upwardly beside the ankle and the lower portion of the leg.

In order that the body of the brace may be snugly adjusted and held about the ankle, straps 14 and 15 are provided at the side portions 3 of the body and extend laterally therefrom and are tapered in the direction of their outer ends, and these straps carry, at their extremities, buckles indicated respectively by the numerals 16 and 17. The straps 14 and 15 are relatively broad where they join the side portion 3 of the body and the strap 14 is located at the top of the said portion 3 and the upper edge of the said strap constitutes a continuation of the upper margin 5 of the body of the brace and extends on a downwardly inclined line, as shown clearly in Figure 2. The straps 14 and 15 are relatively spaced and the lower margin of the strap 15, which margin is indicated by the numeral 18, constitutes a continuation of the front margin 10 of the body of the brace, likewise as shown in Figure 2. Relatively narrow straps 19, 20, 21 and 22 are provided at the side portion 4 of the body and extend laterally therefrom, and are arranged one below another in the order mentioned, the straps 19, 21 and 22 being of substantially the same length and the strap 20 being somewhat longer than the other straps. The buckles 16 and 17, as well as other buckles to be presently described, are of the type embodying a bail, one side of which is provided with a series of sharp prongs, and in order to prolong the life of the straps 19, 20, 21 and 22, the inner sides of the straps are preferably faced by pieces of flexible material such, for example, as cloth, indicated by the numeral 23.

The side portion 4 of the body of the brace is formed with relatively narrow triangular openings 24 and 25, the opening 24

being located substantially opposite and midway between the inner ends of the straps 19 and 20 and, therefore, relatively close to the upper margin of the said side portion of the brace, and the opening 25 being located 70 opposite the inner ends of the straps 21 and 22 and nearer the middle line of the back of the body of the brace than the opening 24. A short strap 26 is secured by stitching or otherwise, to the side portion 4 of 75 the body of the brace at the inner side thereof and extends through the opening 24 and carries a buckle indicated by the numeral 27. A relatively short strap 28 is united to the side of the body of the brace substantially at the seam 12 and carries a buckle indicated by the numeral 29. It will be observed, by reference to Figures 2 and 4 of the drawings, that the buckle 27 is located 80 at the exterior of the body of the brace, the strap 26 which supports the buckle, extending through the opening 24.

In applying the brace, the same is arranged about the ankle substantially in the manner shown in Figure 1, and the strap 14 90 is engaged through the opening 24 and brought about the lower portion of the leg at the outer side of the body of the brace, and the strap 19 is similarly arranged and is engaged through the buckle 16 and adjusted to adapt this portion of the brace to snugly fit about the said lower portion of the leg. In a similar manner, the strap 15 is engaged through the opening 25 and the strap 21 is engaged through the buckle 17, these straps extending exteriorly about the body of the brace at the upper portion of the ankle. The strap 20 is passed around the outer side of the body of the brace between the straps 14 and 15 and the straps 19 and 21, and is adjustably engaged with the buckle 27, as shown in Figure 4, this strap substantially extending entirely about the upper portion of the ankle. The strap 22 is arranged over the arch of the foot and is adjustably engaged with the buckle 29, and all of the straps are snugly arranged and adjusted through the respective buckles so as to adapt the body of the brace to snugly fit about the ankle and lower portion of the leg and likewise about the instep and arch. By forming the openings 24 and 25 triangular, puckering of the adjacent portion of the brace is obviated and the body of the brace is thus enabled to more snugly fit the foot at these portions than would be the case if the openings were straight or merely in the form of slits.

From the foregoing description of the invention, it will be evident that the brace may be conveniently adjusted to the ankle and that the straps may be individually adjusted so that, as a whole, the brace will snugly embrace the ankle and other adjacent portions of the foot referred to.

Having thus described the invention, what I claim is:

An ankle brace comprising a flexible body including an upper ankle embracing portion 5 and a lower foot embracing portion, the upper portion consisting of a back and sides, one of the sides being integral with the back and having a top and two lower short straps and an intermediate long strap, the back 10 having narrow openings opposite the short straps adjacent the long strap, and the other side being stitched to the back by a longitudinally curved seam and having two long straps to pass through the said narrow

openings and receive the short straps in line 15 with said openings to which they are adapted to be buckled, and the lower foot embracing portion forming a part of the back and an extension of the integral side and stitched to the lower end of the stitched on 20 side by a straight seam, the lowermost short strap being adapted to extend over the instep and be buckled to the outer forward corner of the lower foot embracing portion adjacent the straight side seam. 25

In testimony whereof I affix my signature.

MAUDE LUDER. [L. s.]
